UNITED STATES PATENT OFFICE

2,263,999

AUTOMOBILE HEATER

Henry J. De N. McCollum, Chicago, Ill.

Application February 17, 1940, Serial No. 319,555

5 Claims. (Cl. 126—110)

My invention relates generally to automobile heaters, and more particularly to improved electrical circuits and apparatus for controlling the operation of automobile heaters of the internal combustion type.

This application is a continuation in part of my copending application Serial No. 61,213, filed January 28, 1936, which has matured into Patent No. 2,191,173, issued February 20, 1940.

It is an object of my invention to provide an improved means for rendering an automobile heater of the internal combustion type inoperative whenever the temperature of parts of the heater become excessively high due to some abnormal condition.

A further object is to provide an improved control circuit for automobile heaters of the internal combustion type, in which a solenoid-actuated switch is provided to disconnect the electrical portions of the heater from the automobile battery whenever the heater becomes abnormally hot.

A further object is to provide an improved controlling circuit and apparatus for automobile heaters of the internal combustion type which will be effective to render the heater inoperative whenever it attains an abnormally high temperature, and to prevent re-energization of the electrical portions of the heater when the temperature falls to a normal value.

Other objects will appear from the following description, reference being had to the accompanying drawing, in which:

Figure 1 is a fragmentary sectional view of an internal combustion type automobile heater showing the important operating parts thereof; and,

Figure 2 is a schematic wiring diagram showing the improved electrical control circuits.

As shown in Fig. 1, the heater comprises a combustion chamber 10 to which a mixture of fuel and air is supplied by a carbureting device 12, the latter being connected to a suitable source of liquid fuel by a conduit 14. The mixture of fuel and air provided by the carbureting device 12 flows through a tube 16 and impinges upon a baffle plate 18 which has suitable openings formed along the periphery thereof. The combustible mixture in the combustion chamber 10 is ignited by means of an igniter 20 which is preferably in the form of a coil of high resistance wire, such as nichrome wire, and flows from the combustion chamber through passageways formed in a reigniter plug 22 which is preferably made of a ceramic material. The products of

combustion discharged through the passageways in the reigniter 22 flow through a circuitous passageway formed in a radiator casting 24 which is preferably made of an alloy consisting of approximately 95% aluminum and 5% silicon.

The casting 24 is surrounded by a shell 26 preferably made of copper and which has a plurality of fins 28 pressed thereover to provide adequate heat radiating surface for the casting. The flow from the end of the circuitous passageway through the radiator casting 24 is controlled by a control button 28 which is connected to a valve 30 cooperating with a seat 32 formed at the inlet end of a compensator nozzle 34 which has a Venturi-shaped passageway extending therethrough.

When the valve 32 is opened by pulling outwardly on the control button 28, suction is applied to the outlet end of the tortuous passageway through the radiator casting 24 through a conduit 36 which is connected to the intake manifold of the automobile engine, or other suction producing means, and which communicates with the passageway through the compensator nozzle 34. The heating unit is preferably mounted in the passenger compartment of the vehicle, being supported by a plurality of brackets 38 which are bolted to the dash or fire wall 40 of the vehicle which separates the engine compartment from the passenger compartment thereof.

Air from the passenger compartment is circulated downwardly over the radiator by means of a fan 41 driven by an electric motor 42. Means may be provided to admit additional air to make the mixture supplied to the combustion chamber more lean when the heater attains its normal operating temperature, such means being illustrated as a bimetal thermostatic valve 44 which, when cool, closes the end of a passageway 46, and when heated, opens to admit atmospheric air to make more lean the mixture flowing to the combustion chamber.

Means are provided to extinguish the flame in the heater should the fan motor 42 fail to operate normally, or should the heater become excessively hot for any other accidental reason. This means comprises a tube 48 threaded in the combustion chamber casting and carrying a valve seat fitting 50 at its outer end. A valve 52 is cooperable with the seat formed in the end of the fitting 50 and is normally held in engagement therewith by a U-shaped strip 54 of thermostatic bimetal. The bi-metal strip 54 and a bracket 56, which may be of sheet metal, are secured to the valve fitting 50 by a nut 58. When the valve

52 is open, air is admitted through the tube 48 in sufficient quantities to dilute and cool the combustible mixture passing into the combustion chamber, thereby preventing it from burning. Under the influence of excessive heat in the heater, the bi-metal 54 tends to straighten and the free end thereof moves outwardly. The valve 52 and bi-metal 54 are constructed and arranged so that there is lost motion between them, and the free end of the bi-metal 54 will move outwardly a short distance before it moves the valve 52 to admit air to the combustion chamber.

10 The bracket 56 supports a contact 60 which is connected to one terminal of the solenoid 66 and is suitably insulated from the bracket 56. A contact 62, engageable with the contact 60, is carried by the free end of the bi-metal strip 54. The contacts 60 and 62 are positioned and arranged so that the contact 62 engages the contact 60 as the bi-metal strip 54 raises the valve 52 from its seat to put out the burner flame. The bimetal strip is, of course, grounded through its connection with the metallic parts of the heater through the valve fitting 50 and tube 48, although, if desired, an additional grounding connection may be supplied.

15 Without the provision of the contacts 60, 62 and the circuit associated therewith, to be described hereinafter, the bimetal strip 54 will be effective to raise the valve 52 from its seat whenever the temperature of the strip is raised materially above the temperature it attains during normal operation of the heater. If, for example, the motor 42 should fail to operate, the air, instead of being forced downwardly past the 20 radiator, would rise by convection and heat the bimetal strip 54 sufficiently to cause it to open the valve. The opening of the valve would result in the admission of atmospheric air to the combustion chamber in sufficient quantity to render the mixture incombustible. After such occurrence, the heater would of course gradually cool off, and when it had cooled to a sufficiently low temperature, the igniter 20 would again be energized and the heater again commence operating. It would continue in operation until the bimetal strip 54 again became heated sufficiently to open the valve 52, on the assumption that the defect in the means for circulating air downwardly past the radiator was still present. The heater might thus continue such intermittent operation for an extended period of time, with the result that an excessive load would be placed upon the battery of the automobile because of the frequency with which the igniter 20 would be energized under such conditions.

25 To obviate such intermittent operation of the heater, I have provided the control circuit shown in Fig. 2, wherein the contacts 60, 62 are adapted to complete a circuit including the source of electrical energy 64 (usually the storage battery of the automobile) and the winding of a solenoid 66. The plunger of the solenoid 66 is connected to operate a switch 68 which is preferably of the toggle type and which is adapted to connect the motor 42 with the battery 64. The switch 68 also controls the supply of current to a thermostatic switch 70, which, upon closure, energizes the igniter 20. The thermostatic switch 70 is attached to the combustion chamber casting or radiator of the heater so as to be rather rapidly affected by the change in temperature resultant as the heater begins to operate normally. As soon as the temperature of 30 the radiator or the combustion chamber casting,

as the case may be, approaches its normal operating temperature, the thermostatic switch 70 will open and thus disconnect the igniter 20 from the battery 64.

35 5 Should the heater overheat, due to failure of the fan motor 42 or any other reason, the bimetal strip will flex outwardly and carry the contact 62 into engagement with the contact 60, closing the circuit through the solenoid 66 and causing it to open the switch 68 and deenergize the heater circuits. The bi-metal strip 54 will also, under these circumstances, operate the valve 52 to admit air into the combustion chamber, thereby extinguishing the flame. The radiator will then cool and after some time, the bimetal strip 54 will again move to the position in which it is shown in the drawing, holding the valve 52 closed. Such return of the bimetal strip 54 to its normal shape will not, however, result in re-energization of the igniter circuit or the fan motor circuit because the solenoid 66 is not provided with a return spring, and the plunger thereof will therefore remain in the position shown in Fig. 2, and the switch 68 will remain open. If the defect in the system which caused overheating was of a transitory character, the heater will again commence operating in a normal manner as soon as the operator closes the switch 68. If, however, the defect was of a permanent character, the operator of the vehicle will realize this fact after a few attempts to cause the heater to start operating normally by closing the switch 68.

40 45 The control circuit thus provides a convenient means for apprising the operator of the vehicle that there is a defect in the heater. At the same time, the control circuit does not continue to consume energy from the battery, since, as soon as the heater cools to a normal temperature, the contacts 60, 62 will separate and deenergize the solenoid 66, and the igniter circuit and the fan motor circuit will of course remain open due to the open switch 68.

50 55 While I have shown and described a particular embodiment of my invention, it will be apparent to those skilled in the art that numerous variations and modifications thereof may be made without departing from the underlying principles of the invention. I therefore desire, by the following claims, to include within the scope of my invention such similar and modified forms by which substantially the results of the invention may be obtained by substantially the same or equivalent means.

I claim:

60 65 1. In a heater for automotive vehicles, the combination of a radiator located in the passenger compartment of the vehicle, a fan for circulating air from said compartment past said radiator, an electric motor for operating said fan, a source of electric current, a manually operable switch for connecting said source to said motor, thermostatic means located in the path of circulation of air through said heater, a valve operated by said thermostatic means and located to prevent the circulation of heating fluid through said radiator when the temperature surrounding said thermostatic means exceeds a predetermined maximum, a switch operated by said thermostatic means and closed thereby when the flow of heating fluid through said radiator is prevented by said valve, and electromagnetic means controlled by said last mentioned switch to open said manually operable switch when heating fluid is prevented from flowing through said radiator.

70 75 2. In a heater for automotive vehicles, the

combination of a radiator, a fan for circulating air from the passenger compartment of the vehicle past said radiator, an electric motor for operating said fan, a source of electric current, a manually operable switch for connecting said source to said motor, thermostatic means responsive to the temperature of said radiator, a valve operated by said thermostatic means to prevent the flow of heating fluid through said radiator when the temperature thereof reaches a predetermined maximum value, a switch operated by said thermostatic means and closed thereby when heating fluid is prevented from flowing through said radiator, and electromagnetic means controlled by said last named switch to open said manually operable switch when said thermally operable switch is closed.

3. In a vacuum operated automobile heater of the internal combustion type having a combustion chamber operating under vacuum, an electrically operated igniter, a heat radiator, and electrically operated means for circulating air past said radiator, a thermostatic element responsive to the temperature of said air, a valve connecting said combustion chamber with the atmosphere and operated by said thermally responsive means and opened thereby when the temperature thereof exceeds a predetermined maximum value to prevent fuel from burning in said combustion chamber, and a control circuit operated by said thermostatic element to prevent energization of said electrical igniter and said electrically operated means when said valve is open.

4. In an automobile heater of the internal

combustion type having a combustion chamber, an electrically operated igniter, a heat radiator, and an electric motor carrying a fan for circulating air past said radiator, a temperature responsive element, a valve operated by said element to prevent the combustion of fuel in said combustion chamber when said temperature responsive element attains a predetermined high temperature, and a control circuit operated by said element to prevent energization of said electrical igniter and to deenergize said motor whenever said combustion is prevented.

5. In a vacuum operated automobile heater of the internal combustion type having a combustion chamber operating under vacuum, an electrically operated igniter associated with said combustion chamber, a heat exchange device, a temperature responsive switch receiving heat from said heat exchange device, a source of electrical energy, a circuit connecting said source, said temperature responsive switch, and said igniter in series, a manually operable switch in said circuit, means responsive to an abnormal temperature condition of said heater for admitting air to said combustion chamber to prevent the combustion of fuel therein, a contact switch operated by said means, a solenoid having a plunger connected to said manually operable switch and effective upon its energization to open said manually operable switch, and a circuit connecting said contact switch and the winding of said solenoid in series with said source of electrical energy.
